Continuation-in-part of design application Ser. No. 18,112,
July 8, 1969. This application July 14, 1970, Ser. No.
23,946

Term of patent 14 years

Int. Cl. D6—99

U.S. Cl. D33—3

FIG. 1 is a side elevational view of a book end, showing my new design;

FIG. 2 is a rear elevational view;

FIG. 3 is a top plan view;

FIG. 4 is a side elevational view taken from the side opposite to that in FIG. 1;

FIG. 5 is an enlarged cross-sectional detail, taken substantially in the plane of the line 5—5 in FIG. 4; and

FIG. 6 is a rear perspective view on an enlarged scale. The undisclosed front face of the book end is conventionally flat and unornamented.

This application is a continuation-in-part of my co-pending application Ser. No. D. 18,112, filed July 8, 1969, now Pat. No. D. 218,981, dated Oct. 20, 1970.

I claim:

The ornamental design for a book end, as shown and described.
